UNITED STATES PATENT OFFICE.

JAMES M. GAAR, OF NEW YORK, N. Y.

DESIGN FOR A RADIOPHORN.

Application filed August 19, 1924. Serial No. 10,488. Term of patent 3½ years.

To all whom it may concern:

Be it known that I, JAMES M. GAAR, a citizen of the United States, and a resident of the city of New York, borough of Manhattan, in the county and State of New York, have invented a new, original, and ornamental Design for Radiophorn, of which the following is a specification, reference being had to the accompanying drawing, forming part thereof.

Figure 1 is a perspective view of the front of the horn showing my new design; and Figure 2 is a perspective view from the rear of the horn.

I claim:—
The ornamental design for a radiophorn, as shown.

JAMES M. GAAR.
